[57] CLAIM

The ornamental design for a beverage glass or similar article, as shown and described.

DESCRIPTION

FIG. 1 is an elevational view of a beverage glass or similar article depicting my new and ornamental design in the size and proportions of a water tumbler;

FIG. 2 is a top plan view thereof;

FIG. 3 is a bottom view thereof;

FIG. 4 is an elevational view of a beverage glass or similar article depicting my new and ornamental design in the size and proportions of a juice glass;

FIG. 5 is an elevational view of a beverage glass or similar article depicting my new and ornamental design in the size and proportions of an on-the-rocks style of cocktail glass.
